Inventor:

UNITED STATES PATENT OFFICE.

OLIVER HUGHES, OF CALLAO, MISSOURI,

CAR-COUPLING.

SPECIFICATION forming part of Letters Patent No. 376,386, dated January 10, 1888.

Application filed October 11, 1886. Serial No. 215,963. (No model.)

To all whom it may concern:

Be it known that I, OLIVER HUGHES, a citizen of the United States, residing at Callao, in the county of Macon and State of Missouri, 5 have invented certain new and useful Improvements in Car-Couplers, of which the following is a specification.

My invention relates to that class of car-couplers in which the coupling-link is provided 10 centrally with a projecting handle and the draw-heads are extended below the link socket or opening to form forwardly-projecting buffers.

The object of my invention is to produce a 15 coupling of the character stated in which the bumping strain will be transmitted longitudinally of the draw-head, the upper part of the draw-head, above the link-socket, terminating short of the outer ends of the buffers, and the 20 upper face of each buffer being provided with a tapering recess, forming a guideway for the link.

A further object of my invention is a bar 25 coupling-link provided at its ends with vertical openings for the passage of the coupling-pins and centrally with an immovable handle.

The invention consists in particulars of construction and combinations, to be hereinafter described and claimed.

30 In the accompanying drawings, Figure 1 is a vertical longitudinal section showing draw-heads and coupling-link in operative position. Fig. 2 is a perspective view of the coupling-link.

35 The draw-heads A are enlarged at front and provided with an open socket, c, for the reception of the link C, and a vertical aperture for the reception of the coupling-pin D, as is usual.

40 Below the link-socket c the draw-head is extended forward to form a buffer, B', the distance from the bottom of said socket to the bottom of the buffer being greater than the distance from the top of said socket to the top of the draw-head, thus presenting a large body of metal to receive the shock occasioned by the 45 coming together of two cars, as in coupling, reversing the engine, &c. It will be noted also that the lower part of the shank A' of the

draw-head is nearly on a line with the bottom 50 of the buffer B', whereby the bumping shock is communicated longitudinally through the draw-head, and a tendency to fracture is avoided.

The sides of the link-socket are formed by 55 webs c', which are extended forward to the front outer corners of the buffer B', thus forming a tapering recess or guideway for the link C.

The link C is constructed, preferably, of a 60 bar of malleable iron, provided at each end with a vertical aperture for the passage of the coupling-pin D. These apertures may be formed by a punch or otherwise. The link is provided centrally with a permanently and 65 rigidly secured upwardly-projecting handle, E, of a form to be conveniently grasped by the hand when inserting the end of the link or removing it, and is of such length that the hand-hold e will be above the abutting 70 faces of the buffers or the webs c', thus insuring safety to the hand in coupling or uncoupling.

I am aware that a draw-bar having a buffer 75 formed by a base-extension from the open end draw-bar, leaving a clear way above said buffer for the direct handling of the link, is not new; and I am also aware that it is not new to provide a coupling-link with a removable key or hand hold, nor to provide a horizontal bar 80 or rod cast with independent links, nor to combine with a hand-plate having an aperture the ordinary coupling-link having its side bars brought together at about the center and held 85 thereat in said aperture, and these features I do not claim.

What I do claim, and desire to secure by Letters Patent, is—

1. In a car-coupler, a draw-head provided below the link-socket with a downwardly-extending buffer, the bottom of which is nearly in a plane with the bottom of the shank of the draw-head and having its upper face in a plane with the bottom of the link-socket, the side walls of said link-socket being extended forward divergently to form a tapering guideway for the link, substantially as described.

2. In combination with a draw-head constructed substantially as described, a coupling-link consisting of a flat metal bar provided at each end with an elongated aperture
5 for the passage of a coupling-pin and centrally with a permanently and rigidly secured upwardly-projecting handle, E, of such length

that the hand-hole e will be above the upper edges of the webs c' of the buffers, for the purpose set forth.

OLIVER HUGHES.
